Des. 185,782
Patented Aug. 4, 1959

185,782

ARM BAND

Hyman B. Lasting, Portsmouth, Va.

Application August 8, 1958, Serial No. 52,142

Term of patent 7 years

(Cl. D3—10)

Fig. 1 is a top plan view of an arm band showing my new design, the reverse side thereof being plain and unornamented; and

Fig. 2 is an edge elevational view thereof.

I claim:

The ornamental design for an arm band, as shown and described.
